UNITED STATES PATENT OFFICE.

HAROLD A. REICH, OF NEW YORK, N. Y., ASSIGNOR TO ALEXANDER D. REICH AND
HAROLD A. REICH, COPARTNERS TRADING UNDER NAME OF R. REICH & SON, OF
NEW YORK, N. Y.

METHOD OF CUTTING FUR SKINS AND PRODUCT THEREOF.

Application filed March 1, 1924. Serial No. 696,112.

To all whom it may concern:

Be it known that I, HAROLD A. REICH, a citizen of the United States of America, residing at New York city, county of New York, State of New York, have invented certain new and useful Improvements in Methods of Cutting Fur Skins and Products Thereof, of which the following is a specification.

10 This invention relates to an improved method of cutting fur skins, particularly muskrat skins, and to the resulting garments or other products thereof.

Heretofore, it has been customary to cut dressed muskrat skins by severing to retain the so-called back or "groetzen" portion, the severed portions being discarded or employed with furs of other animals. Such prior practice leads to the formation of 20 garments formed of the major portion of the muskrat skin and procuring a high marketable value but subject to considerable losses owing to the low market value of garments made from the severed-off portions of the skins.

Pursuant to the present invention, each dressed muskrat skin is divided into three portions, to wit, the "groetzen" portion solely, the opposite "belly" portions and intermediate portions disposed on each side of the dressed muskrat skin between the back portion and the "belly" portion. The resulting desired garments are of three types, namely, garments formed substantially solely of the "groetzen" portion, the second type of garments formed substantially solely of the intermediate portions and the third type of garments formed substantially solely of the "belly" portions.

40 I have discovered that such garments of their respective types possess distinctive characteristics of color and hair formation and distribution and derive greatly increased market values for all of the respective three types.

Further features and objects of the invention will be more fully understood from the following detail description and the accompanying drawings, in which—

50 Fig. 1 is a rear plan view of a dressed muskrat skin, showing the manner of cutting the same for attaining the invention;

Fig. 2 is an elevational view of a gar-

ment formed substantially solely of the "groetzen" portion of the skin;

Fig. 3 is an elevational view of a garment formed substantially solely of the "belly" portions of the skin; and

Fig. 4 is an elevational view of a garment formed substantially solely of the intermediate portions of the skin.

Referring to the drawings, the skin 10 represents the usual finished muskrat skin.

Pursuant to the invention, the skin is divided by ruled lines or equivalent marking 15 into the "groetzen" portion 11, disposed between the lines 12, 13. The two oppositely disposed "belly" portions 14, 15 are disposed between the lines 16, 17 and the outer lateral edges of the skin. Accordingly, the intermediate portions 18, 19, lie on opposite sides of the "groetzen" portion 11 and are respectively disposed between the lines 12 and 16 and the lines 13 and 17.

One type 20 of garments or other fur products is formed substantially solely of the "groetzen" portions 11 of the required number necessary to complete each garment, the fur portions being assembled as strips by sewings or otherwise, as will be understood. The resulting garment is indicated in Fig. 2 from which it will be perceived that the fur thereof is formed of fur portions of substantially uniform dark tone and substantially uniform characteristics of hair 25 formation and distribution.

A second type 21 of garments or other fur products is formed from the intermediate portions 18, 19, by assembling as strips secured by sewings or otherwise, as will be understood, and results, as indicated in Fig.

3 in a new type of fur garment formed substantially of fur portions of substantially uniform tone and substantially uniform characteristics of hair formation and distribution. This second type 21 of garment is of a lighter tone than of the aforesaid first type 20 of garment.

The third type 22 of garments or other fur product is formed from the "belly" portions, 14, 15, sewed as strips or otherwise secured, as will be understood. This third type of garment comprises substantially solely such "belly" portions and results in a new type of garment of substantially uniform 100 tone and substantially uniform hair forma-

tion and distribution. The tone of the third type 22 of garments is lighter than the tone of the second type 21 of garments.

From the above, it will be apparent that my invention provides for the utilization of the entire parts of finished muskrat skins and like forms of skins of other animals. The resulting products possess enhanced values by reason of the substantially uniform tone and substantially uniform formation and distribution of hair, for the three respective types.

Whereas I have described my invention by reference to specific forms thereof, it will be understood that many changes and modifications may be made without departing from the spirit of the invention.

I claim:

1. The method of cutting and connecting dressed fur skins of muskrats and the like, which comprises segregating each skin into three portions by four lines of cutting into a central or "groetzen" portion, two "belly" portions and two portions intermediate said central or "groetzen" portions and the respective "belly" portions, connected to one another the central or "groetzen" portions of the respective skins to form a fur product, connecting to one another the "belly" portions of the respective skins to form a fur product, and connecting to one another the intermediate portions of the respective skins to form a fur product.

2. The method of cutting and connecting

dressed fur skins of muskrats and the like, 35 which comprises segregating each skin into three portions by four lines of cutting into a central or "groetzen" portion, two "belly" portions and two portions intermediate said central or "groetzen" portion and the respective "belly" portions and connecting to one another the central or "groetzen" portions of the respective skins to form a fur product.

3. The method of cutting and connecting 45 dressed fur skins of muskrats and the like, which comprises segregating each skin into three portions by four lines of cutting into a central or "groetzen" portion, two "belly" portions and two portions intermediate said 50 central or "groetzen" portion and the respective "belly" portions and connecting to one another the "belly" portions of the respective skins to form a fur product.

4. The method of cutting and connecting 55 dressed fur skins of muskrats and the like, which comprises segregating each skin into three portions by four lines of cutting into a central or "groetzen" portion, two "belly" portions and two portions intermediate said 60 central or "groetzen" portion and the respective "belly" portions and connecting to one another the intermediate portions of the respective skins to form a fur product.

In testimony whereof I have signed this 65 specification this 27th day of February, 1924.

HAROLD A. REICH.
